UNITED STATES PATENT OFFICE.

GEORGE GOTHIER, OF LOS ANGELES, CALIFORNIA.

RAILROAD SPIKE.

Application filed August 24, 1925. Serial No. 52,073.

This invention relates to improvements in railroad spikes and the like.

Heretofore considerable difficulty has been experienced in keeping spikes driven into ties of a railroad tight. As the train passes over the rails, the ties are compressed and the rail sinks an appreciable amount while the weight of the train is upon it. The rails are normally supported upon the ties by means of anchor or bed plates, and after the train has passed on, the rails spring back into their normal position, so that during the course of time after a large number of trains have passed over the rails, the spikes gradually creep up out of the ties, so that it is necessary from time to time to have the spikes driven back into the ties.

An object of this invention is to provide an improved form of railroad spike, which after it has been once driven into the tie through the anchor or bed plate will always maintain the same position with respect to the anchor plate, and in this manner the spike will not loosen or creep upwardly.

Another object of this invention is to provide a spike which has its head and part of the shank slotted, and which may be driven into the tie through an anchor plate. A wedge is also provided which is driven into the slot after the spike has been driven into place and this wedge serves to spread the upper end of the spike so as to firmly maintain it on the anchor plate.

A further object of this invention is to provide a spike having a head which projects materially from one side of the spike, the opposite side of the spike being gradually tapered toward the axis of the shank of the spike for a purpose hereinafter to be described.

With the foregoing and other objects in view which will be made manifest in the following detailed description and specifically pointed out in the appended claims, reference is had to the accompanying drawings for an illustrative embodiment of the invention wherein:

Figure 1 is a sectional view through a tie and through a rail and anchor plate thereon, one spike of the improved form of construction being shown in elevation and the other spike being shown in vertical section,

Fig. 2 is a vertical section through the end of the tie, illustrating the spike of the improved construction in applied position,

Fig. 3 is a side elevation of the improved railroad spike,

Fig. 4 is a side elevation taken at right angles to the view shown in Fig. 3,

Fig. 5 is a side elevation of the wedge, and

Fig. 6 is an end elevation of the wedge.

Referring to the accompanying drawings wherein similar reference characters designate similar parts throughout, the improved railroad spike consists of a shank 10, on which is formed the conventional head 11, which projects materially from one side of the shank, as indicated at 12. The side 13 of the shank from which the head projects materially is preferably parallel to the axis of the shank, while the side 14 which is opposite the side 13 is tapered downwardly toward the axis of the shank. The two sides 13 and 14 converge adjacent the bottom of the shank, forming an edge 15. A slot 16 is formed in the head 11 and extends downwardly into the top of the shank of the spike. Above the bottom of the slot 16, two shoulders 17 and 18 are formed which are arranged upon those sides of the spike which are not slotted.

A wedge 19 is also provided, which has a head similar in form to the shape of the head 11 on the spike. The lower end of the wedge 19 is slotted, as indicated at 20, so as to bifurcate the wedge. On the two end edges of the wedge shoulders 21 and 22 are formed, which are so positioned that when the wedge is driven into the slot 16, the shoulders 21 and 22 will be approximately horizontally even with the shoulders 17 and 18 on the shank of the spike.

In Fig. 1 the tie is indicated at T, on which the rail R is positioned, there being an anchor plate A located between the bottom of the rail and the tie. These anchor plates have apertures therein for the reception of the railroad spikes, this being conventional construction. The spikes are first driven into the apertures in the anchor plate A, and when the shoulders 17 and 18 encounter the anchor plate, they force the upper ends of the shank and the separated parts of the head 11 together, while the shoulders pass through the apertures. The shoulders are so arranged that when the under side of the projection 12 of the head 11 engages the top of the base flange of the rail R, the shoulders will be even with the under side of the anchor plate A. In this

manner as the spike is driven home, the projection 12 engages the top of the base flange of the rail, and the upper portions of the shank of the spike separate because of the resiliency of the metal of which they are made. In this manner the shoulders occupy positions beneath the bottom of the anchor plate A, as shown in Fig. 1. In some cases the spike alone may be used, but preferably the wedge shown in Figs. 5 and 6 is employed in addition thereto. When the wedge is driven into the slot 16, the lower portions of the wedge which are separated by the slot 20 move toward each other as the shoulders 21 and 22 ride or slip over the edges of the anchor plate about the apertures therethrough. When the wedge 19 has been driven home in the slot 16, the shoulders 21 and 22 will be so positioned that the lower portions of the wedge will spread, and these shoulders will also occupy positions bearing against the under side of the anchor plate A.

In this manner when the improved railroad spike is applied, there will be a firm, rigid connection between the anchor plate and the body of the spike. Consequently, as the trains pass over the rails, pressing the anchor plate down into the tie, the spikes move downwardly with the anchor plate into the tie. Consequently, as the various trains pass over the rails, the spikes are being continually driven downwardly into the tie and will always keep tight. Furthermore, it is impossible for the spikes to creep upwardly through the anchor plate. Because of the fact that the spike is always being driven into the tie, a smaller spike can be used than the ordinary spike heretofore employed. This has the advantage over the ordinary spike in that some difficulty has been experienced because of the fact that the spikes heretofore employed frequently split the ties on being driven into them.

It will be noted that the projection 12 on the head 11 is always extending toward the rail R so as to firmly fasten the rail R against the anchor plate A and to the tie T. By making the side 14 tapered with respect to the axis of the shank 10, as the spike is being driven home, it will gradually move toward the rail. Consequently, when the spike has been driven home, it will bear against the edges of the base flanges of the rail, and will be quite tight.

Another advantage of the improved railroad spike develops from the edges afforded by the slot 16 and the edges upon the wedge. These edges are on those surfaces which bear against the top surface of the base flanges of the rail; and because of the fact that the edges are fairly sharp, they will tend to dig into the base flanges, thus preventing or resisting longitudinal shifting of the rail.

In some places, such as on curves or at

switches or crossings, where it is contemplated that the rails may be subsequently removed or replaced, the wedge is not inserted into the head of the spike, but is left out. The spike is merely driven into the tie and if the conventional spike puller or crowbar is applied to the spike, it will cause the portions of the head to move toward each other in pulling the spike so that the shoulders 17 and 18 will be drawn together a sufficient distance to permit the spike being pulled through the anchor plate.

From the above it will be appreciated that an improved railroad spike is provided which will always be kept tight, thus reducing large costs to railroads in keeping track walkers busy walking along the track and tightening the spikes which ordinarily loosen from time to time.

It will be understood that various changes may be made in the detail of construction without departing from the spirit or scope of the invention as defined by the appended claims.

I claim:

1. A railroad spike having its head and the upper end of its shank slotted, a shoulder formed on the side of the shank above the bottom of the slot, and a wedge adapted to be driven into the slot so as to separate the head and the upper end of the shank, said wedge having a shoulder formed thereon adapted to be positioned horizontally even with the shoulder on the shank when the wedge is driven into the slot so as to project from an unshouldered side of the shank.

2. A railroad spike having its head and the upper end of its shank slotted, a shoulder formed on the side of the shank above the bottom of the slot, and a wedge adapted to be driven into the slot so as to separate the head and the upper end of the shank, said wedge being bifurcated and having a shoulder formed on an end edge adapted to be positioned horizontally even with the shoulder on the shank when the wedge is driven into the slot.

3. A railroad spike comprising a shank having a head formed on its upper end which projects materially from one side of the shank, there being a slot formed in the head longitudinally thereof, which slot extends downwardly into the shank, there being shoulders formed on the unslotted sides of the shank as and for the purpose described, and a wedge adapted to be driven into said slot, said wedge being bifurcated and having shoulders formed upon its end faces which are adapted to be positioned horizontally even with the shoulders on the shank when the wedge is driven into said slot.

4. A railroad spike comprising a shank having a head formed upon its upper end

which projects materially from one side of the shank, there being a slot formed in the head longitudinally thereof which extends downwardly into the shank, there being shoulders formed on said shank, and a wedge adapted to be driven into said slot having a head projecting materially from one edge thereof adapted to be positioned between the divided projecting portion of the head on the shank, said wedge being bifurcated from its bottom upwardly and having shoulders formed on its edges. ¹⁰

In testimony whereof I have signed my name to this specification.

GEORGE GOTHIER.
